CIRCUIT CONTROLLING DEVICE

George H. Leland, Dayton, Ohio, assignor to The
Leland Electric Company, Dayton, Ohio, a cor-
poration of Ohio

Application August 4, 1937, Serial No. 157,365

22 Claims. (Cl. 200—11)

This invention relates to a circuit controlling device and is adapted for various uses, such as a voltage changer, a reversing switch, or the like.

One object of the invention is to provide a circuit controlling device which will be simple in construction, compact in form and may be produced at a low cost.

A further object of the invention is to provide such a device in which the stationary contacts will be arranged substantially in a common plane and the movable contactors will be rotatable into circuit closing engagement with selected contacts, and which will have means for causing the contactors to firmly engage all of the selected contacts.

A further object of the invention is to provide such a device which can be adapted to different uses by changing the arrangement and the electrical connections of the stationary contacts and without substantial structural changes.

Other objects of the invention may appear as the device is described in detail.

In the accompanying drawings Fig. 1 is a sectional view of a portion of an electric motor showing my circuit controlling device installed therein to function as a voltage changer; Fig. 2 is a front elevation of the circuit controlling device; Fig. 3 is a front elevation of the base with the movable member removed; Fig. 4 is a rear elevation of the device, partly broken away; Fig. 5 is a rear elevation of the movable member; Fig. 6 is a section taken on the line 6—6 of Fig. 2; Fig. 7 is a diagrammatic illustration of the device as shown in Figs. 1 to 6; Fig. 8 is a diagrammatic illustration of a form of the device adapted to function as a reversing switch; Fig. 9 is a diagrammatic illustration of another form of device adapted to function as a reversing switch; Fig. 10 is a diagrammatic illustration of a third form of the device adapted to function as a reversing switch; Fig. 11 is a detail view showing the bridging relation of one of the contactors with one pair of stationary contacts; Fig. 12 is a front elevation, partly broken away, of a modified form of the device adapted to control a plurality of circuits; Fig. 13 is a front elevation, partly broken away, of another modified form of the device adapted to control a relatively large number of circuits; Fig. 14 is a section taken on the line 14—14 of Fig. 13; and Fig. 15 is a section taken on the line 15—15 of Fig. 13.

In the drawings I have illustrated certain embodiments of my invention and have illustrated the same as adapted for the most part for use with electric motors but it will be understood

that the invention may take various forms and may be used for various purposes.

In that embodiment of the invention illustrated in Figs. 1 to 6 the device comprises a base 20 adapted to be mounted on a suitable support, 5 such for example as the frame of an electric motor shown in Fig. 1. This base is provided with a circumferential flange 21 extending in the direction of its axis and providing in the outer face of the base a circular cavity 22, the rear wall of which 10 is preferably flat. Mounted in the base and projecting into the cavity are a plurality of contacts, in the present instance six, as shown at 23, 24, 25, 26, 27 and 28. The number and arrangement of these contacts is determined by the particular use to which the device is to be put. In the arrangement here shown the contacts 23 to 26 are terminal contacts rigidly mounted in the base and provided on the rear side of the base with binding posts 29, here shown as screws having their heads arranged in cavities 30 formed in the rear side of the base. The contacts 27 and 28 are not terminal contacts but are electrically connected one to the other. In the present instance they are formed integral with a bar or 20 jumper 31 embedded in the base. The several contacts project into the cavity 22 substantially uniform distances so that they are located substantially in a common plane.

A rotatable member 32 is mounted on the base 30 for rotatory movement about an axis extending transversely to the plane of said contacts. In the present instance this movable member is disk-like in form and extends into the cavity 22. It is provided with a central boss 33 which extends into a recess 34 in the base and serves as a guide, the end of the boss being spaced normally from the closed end of the recess to permit the movable member to have axial movement, as well as rotary movement, with relation to the base. The 40 movable member 32 is provided on its rear or inner surface with contactors 35 and 36 which, in the present instance, are arranged on opposite sides of the axis of the member and adapted to be moved into bridging engagement with selected pairs of contacts in the cavity 22. The movable member is yieldably pressed toward the stationary contacts and, in the present instance, the movable member 32 and the base are provided with aligned openings 37 and 38 through which 50 extends a tightly coiled spring 39 which is connected at its outer end with a suitable part adapted to form a stop, such as a screw 39a the head of which is preferably located in a recess 40 in the outer side of the movable member. The 55

other end of the spring is provided with a suitable loop or eye 41 adapted to receive a pin 42 which extends across the end of the opening 38 in the base and is preferably located in a recess 43 in the rear or inner side of the base. In assembling the device the spring is inserted through the aligned openings and a suitable implement engaged with the eye 41 and the spring stretched to move the eye beyond the end of the opening 38 and thus permit the pin to be inserted, after which the spring is released and the pin engages the shoulder at the rear end of the opening 38 to hold the spring under tension. This spring forms the sole connection between the movable member 32 and the base and thus serves not only as a pressure device but also as a pivot for the movable member. The disk-like movable member 32 is of a diameter less than the diameter of the cavity 22 and the boss 33 is of a less diameter than the recess 34, so as to provide a clearance between the movable member and the base which will enable the movable member to have a slight lateral movement with relation to the base and to tilt about an axis transverse to the axis of rotation, in all directions, and thus permit the contactors 35 and 36, under the influence of the central spring 39, to adjust themselves to the selected stationary contacts and to engage the respective contacts with substantially equal resilient pressure. Preferably the contacts which are to be bridged by the contactors have their contact surfaces inclined so that they converge toward the end wall of the cavity 22 and, as here shown, the terminal contacts 23 to 26 have frusto-conical ends and the jumper contacts 27 and 28 are in the form of lugs beveled on one edge. The contactors 35 and 36 are of such length that they will enter the space between the contacts which are to be bridged and their ends are preferably beveled or rounded to enable them to engage the converging contact surfaces of the stationary contacts with a camming or wedging action which provides a very firm engagement therewith. When the movable member is rotated, as by means of a finger piece 44, each movable contactor will ride up the inclined surface of one of the contacts with which it is in engagement and move across the end of that contact toward another bridging position, and as soon as the inclined ends of the contactors overlap the inclined surfaces of the selected stationary contacts the contactors will be moved by the spring 39 into firm engagement with said inclined surfaces, with what is in effect a snap action, the inclined or cam surfaces of the contacts serving to accurately position the contactors with relation thereto.

In the particular embodiment illustrated in Figs. 1 to 6 the contacts are arranged for use as a voltage changer and are connected in circuits as shown in Fig. 7. As there illustrated the contact 24 is connected with one side 45 of a main current supply line and the contact 26 is connected with the other side 46 of said main line. The contacts 23 and 24 are connected with the respective ends of one of the motor windings 47 and the contacts 25 and 26 are connected with the respective ends of a second motor winding 48. With the contactor 35 in engagement with the contacts 23 and 27 and the contactor 36 in engagement with the contacts 25 and 28, as shown in full lines in Fig. 7, the current will flow from the line 45 through contact 24, winding 47, contact 23, contactor 35, contact 27, jumper 31, contact 28, contactor 36, contact 25, winding 48 and contact 26 to the other side 46 of the main line

and the two windings will be connected in series. When the contactors 35 and 36 are in the position shown in dotted lines in Fig. 7, where the contactor 35 connects contacts 23 and 26 and the contactor 36 connects contacts 24 and 25, the current from the side 45 of the line will divide at contact 24 and a part of that current will flow through the winding 47, contact 23, contactor 35, and contact 26 to the side 46 of the line, the other part of the current will flow through the contactor 36, contact 25, winding 48, and contact 26, to the side 46 of the line, thus connecting the two windings in parallel.

It is desirable that the movable member should have but two operative positions and that it should be positively prevented from moving substantially beyond either operative position. In the present construction the flange 21 of the base has a portion of its edge cut away to provide a recess 49 and the finger piece 44 is provided with an extension 50 which extends into that recess, the ends of the recess forming stops which positively limit the rotatory movement of the movable member 32 in both directions. Preferably the base is provided with indicating marks, such as the numbers 110 and 220, with which cooperates a suitable pointer carried by the movable member and which, in the present instance, is formed by the tapered end 51 of the finger piece 44. When the movable member is at one limit of its rotatory movement the pointer will be directed toward the number 220, indicating that the windings are connected for operation on 220 volts, and when the movable member is at the other limit of its rotatory movement the pointer will be directed toward the number 110, indicating that the windings are connected for operation on 110 volts. If desired, the device when installed on the motor may be enclosed by a suitable housing which will exclude dirt and combustible gases and is here shown as a hollow cap 52 having screw threaded connection with the motor frame.

In Fig. 8 I have illustrated an arrangement of the device adapted for reversing the direction of flow of the current through an electric motor or other electrical power translating device. In this embodiment the construction and arrangement of the base, movable member and contactors is substantially identical with that heretofore described and the same number of stationary contacts are employed in substantially the same arrangement but have different electrical connections. As there shown, the contact 54 is connected with one side 55 of the main line and the contact 56 is connected with the other side 57 of the main line. The contact 58 is connected with one end of a motor winding 59 and the contact 60 is connected with the other end of that motor winding. The contact 61 is connected with the contact 60 by a jumper 62 and the contact 63 is connected with the contact 58 by a jumper 64. When the contactors, indicated at 65 and 66, are in the full line positions shown in Fig. 8, in which the contact 54 is connected with the contact 58 and the contact 56 is connected with the contact 60, the current from the side 55 of the line will flow through the contact 54, contactor 65, contact 53, through the winding 59 in the direction of the full line arrow, through the contact 60, contactor 66 and contact 56 to the other side 57 of the main line. When the contactors are shifted to their dotted line positions, to connect the contact 54 with the contact 61, and the contact 56 with the contact 63, the current will flow from the side 55 of the main line through contact 54, contactor 65

65, contact 61, jumper 62, contact 60, through the winding 59 in the direction of the dotted line arrow, contact 58, jumper 64, contact 63, contactor 66, contact 56 to the side 57 of the main line, thus causing the current to flow in a reverse direction and reversing the direction of operation of the motor.

In Fig. 9 I have shown another arrangement of contacts in which the current may be reversed by the use of four contacts only. As there shown, the contact 67 is connected to one side of the main line 68 and the contact 69 is connected with the other side 70 of the main line. The contact 71 is connected with one end of the winding 72 and the contact 73 is connected with the other end of that winding. When the contactors 74 and 75 are in their full line positions the current will flow from the side 68 of the main line through contact 67, contactor 75, contact 73, and through the winding 72 in the direction of the full line arrow, through contact 71, contactor 74, and contact 69 to the side 70 of the main line. When the contactors are moved to their dotted line positions the current will flow from the line 68 through contact 67, contactor 75, contact 71, through the winding 72 in the direction of the dotted line arrow, through contact 73, contactor 74 and contact 69 to the side 70 of the main line.

In Fig. 10 I have illustrated another arrangement constituting a reversing switch for a motor of that type which embodies a main winding and two starting windings, the latter being so arranged that when energized one of them will start the motor in one direction and the other will start the motor in the other direction. In this form the structural features are similar to those above described, and the base 20 is again provided with six stationary contacts. The contact 78 is connected with one end of the main winding 79, the other end of which is connected with one side 80 of the main line, and the contact 81 is connected with the other side 82 of the main line. The contact 83 is connected with one end of the starting winding 84, the other end of which is connected directly with the side 80 of the main line. The contact 85 is connected to one end of a second starting winding 86, the other end of which is connected directly with the side 80 of the main line. A contact 87 is connected by a jumper 88 with the contact 78 and the contact 89 is connected by a jumper 90 with the contact 81. With the contactors 91 and 92 in the positions indicated in full lines, a part of the current from the main line flows through the main winding 79, contact 78, contactor 92 and contact 81 to side 82 of the main line, and another part of the current from the side 80 of the main line will flow through the starting winding 86, contact 85, contactor 91, contact 89, jumper 90 and contact 81 to the side 82 of the main line. When the contactors are moved clockwise to their dotted line positions a part of the current will flow from the side 80 of the main line through the main winding 79, contact 78, jumper 88, contact 87, contactor 92 and contact 81 to the side 82 of the main line, and another part of the current from the line 80 will flow through the starting winding 84, contact 83, contactor 91, contact 89, jumper 90, and contact 81 to the side 82 of the main line. Thus when the contactors are in one position the current will flow through one starting winding to start the motor in one direction and when the contactors are in another position the current will flow through the other starting winding to start the motor in the other

direction, current flowing through the main winding in the same direction in both positions of the contactors. When the contactors are in intermediate positions, in which they would respectively engage the contacts 81 and 89 only, all circuits are broken and the motor is idle.

In Fig. 12 I have shown another form of the device which is adapted to simultaneously connect a plurality of contacts in selected pairs. The base 20 and rotatable member 32 are substantially identical with those heretofore described. The base may be provided with any suitable number of contacts, preferably arranged in circular series. As here shown, the contacts are arranged in three groups and each group includes three contacts, 94, 95 and 96. The circuit connections for the contacts are not shown as they will vary according to the use to which the device is to be put. The rotatable member is provided with three contactors 97 arranged to cooperate respectively with the several groups of stationary contacts, each contactor being of such length that it will connect the central contact of each group with either of the other contacts of that group. When the rotatable member is in the position shown in Fig. 12 the contacts 94 and 95 of each group will be connected one with the other and when the rotatable member is moved clockwise the contacts 95 and 96 will be connected one to the other. Obviously the number and arrangement of the contacts and contactors may be varied to conform to the particular use to which the device is to be put.

In Figs. 13, 14 and 15 I have shown a form of the device adapted to control a relatively large number of circuits. The base 100 is similar in construction to the base 20 and is provided with an outer series of contacts which, in the present instance, includes three pairs of contacts 101, and is also provided with an inner series of contacts which, as here shown, comprises six contacts 102 spaced equal distances apart. Two pairs of contactors, 103 and 104, and 105 and 106 are provided to cooperate with the respective series of stationary contacts. In order that the several contactors may adjust themselves into firm engagement with the respective pairs of contacts they are carried by separate rotatable members. As is shown the outer contactors 103 and 104 are carried by a main rotatable element 107 which is similar to the rotatable member heretofore described except that it is provided in its inner side with a cavity 108. Mounted in this cavity is a second rotatable member 109 which is connected with the outer member 107 for rotation therewith, as by means of lugs 110 carried by the inner member and extending into slots 111 in the outer member. The contactors 103 and 104 are arranged on diametrically opposite sides of the axis of the outer rotatable member 107 and the contactors 105 and 106 are arranged on diametrically opposite sides of the inner rotatable member 109. The contactors of the two pairs are arranged in transverse alignment. It will be obvious, however, that the several contactors may be arranged in any desired relative positions. The outer member 107 is connected with the base 100 by a coiled spring 112 and the inner member 109 is connected with the base by a coiled spring 113 of larger diameter than the spring 112 and arranged about the same, both being connected with the pin 114 which holds them under tension, thereby causing each rotatable member to be separately pressed toward the respective stationary contacts. The outer rotatable member is of

such size as to provide clearance between the same and the base and thus permit it to tilt in the manner heretofore described. The inner member 109 is of slightly smaller diameter than the cavity 108 and the lugs 110 are of smaller size than the recesses 111, thereby providing a clearance between the two members and permitting both members to tilt with relation one to the other and with relation to the base, whereby the 10 contactors will automatically adjust themselves into firm engagement with the selected pairs of contacts.

In the arrangement shown the rotatable members may be actuated to move one or the other 15 of the outer contactors 103 or 104 into bridging relation to one or the other of the outer pairs of contacts 101 and when so positioned there will be no connection between any of the contacts of the inner series. When adjusted to other positions 20 the inner contactors 105 and 106 will simultaneously bridge two pairs of contacts 102 of the inner series and none of the contacts of the outer series will be connected. It will be understood of course that the number and arrangement of 25 the contacts and contactors may be varied according to the use to which the device is to be put.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

35 1. In a circuit controlling device, two rigid members at least one of which is biased toward the other and one of which is tilttable with relation to the other, a plurality of contacts carried by one of said members in opposed relation to the 40 other member and adapted to be connected in pairs, and a plurality of contacts carried by the other member and provided with not less than two or more than three pairs of contact surfaces arranged to engage a corresponding number of 45 pairs of the first mentioned contacts, said contacts being shaped and arranged to cause the contacts on said tilttable member to be wedged into lateral engagement with the cooperating contacts on the other member and to permit said 50 tilttable member to have pivotal movement about two axes with relation to said cooperating contacts.

55 2. In a circuit controlling device, two opposed rigid members at least one of which is biased toward the other, a plurality of contacts carried by one of said members and adapted to be selectively connected in pairs, a plurality of contactors carried by the other of said members, there being not less than two or more than three such contactors, one of said members being tilttable to enable said contactors to have simultaneous engagement with selected pairs of contacts, said contactors and said contacts being shaped and arranged to permit each contactor to have both 60 lateral movement and pivotal movement to cause the same to firmly engage both contacts of the selected pair of contacts, and to permit said contactor to have pivotal movement about a second axis transverse to the axis of the first mentioned 65 pivotal movement.

70 3. In a circuit controlling device, two opposed rigid members at least one of which is biased toward the other, a plurality of contacts carried by one of said members and adapted to be selectively connected in pairs, a plurality of contactors

carried by the other of said members, there being not less than two or more than three such contactors, one of said members being tilttable to enable said contactors to have simultaneous engagement with selected pairs of contacts, each 5 contactor being arranged to have lateral wedging engagement with the contacts of the selected pair of contacts and the cooperating contact surfaces being shaped to permit said contactor to have pivotal movement about two axes with relation to said pair of contacts.

4. In a circuit controlling device, a non-rotatable rigid member, a rotatable rigid member mounted in opposed relation to said non-rotatable member for tilting movement with relation 15 thereto, at least one of said members being biased toward the other member, a plurality of contacts carried by said non-rotatable member and adapted to be connected in pairs, a plurality of contactors carried by said rotatable member and 20 each adapted to bridge a pair of said contacts and each contactor being arranged to have lateral wedging engagement with the bridged contacts at points spaced from the bottoms thereof and having its contact surfaces curved substantially 25 about a common axis transverse to the axis of rotation of said rotatable member.

5. In a circuit controlling device, two opposed rigid members biased one toward the other, contacts carried by one of said members, contactors carried by the other member and each adapted to bridge a pair of contacts on the first mentioned member, one of said members being tilttable with relation to the other member and said contacts and said contactors being so shaped that each 35 point of engagement will comprise a narrow arcuate surface arranged to permit said tilttable member to move about two intersecting axes, whereby all of said contactors may be brought into firm engagement with both contacts of the 40 respective pairs of contacts.

6. In a circuit controlling device, a base, a plurality of stationary contacts mounted on said base and arranged to be connected in pairs, a member biased toward said base and mounted for rotary 45 movement and for axial movement with relation thereto, and contactors carried by said member and movable thereby into bridging relation respectively with selected pairs of stationary contacts, the stationary contacts of each pair being 50 arranged to permit the bridging contactor to enter the space between them and said member being tilttable about a plurality of axes to cause said contactors to engage the respective contacts with substantially equal pressure.

7. In a circuit controlling device, a base, a plurality of stationary contacts mounted on said base substantially in a common plane and arranged to be connected in pairs, the contacts of each pair having surfaces converging toward said base, a member mounted on said base for both rotatory and axial movement with relation thereto, contactors mounted on said member and movable thereby into a position between and in engagement with the converging surfaces of selected 65 pairs of contacts, and means for yieldably pressing said member toward said base, said member being free to so adjust itself that said contactors will have firm engagement with each contact of the respective pairs of contacts.

70 8. In a circuit controlling device, a base, a plurality of stationary contacts mounted on said base substantially in a common plane and arranged to be connected in pairs, the contacts of each pair having contact surfaces converging toward said 75

base, a member mounted on said base for both rotatory movement and axial movement with relation thereto, a plurality of contactors carried by said member and movable thereby into engagement respectively with the converging surfaces of selected pairs of contacts, said member being tiltable about a plurality of transverse axes to enable said contactors to have simultaneous engagement with the contacts of the respective pairs of contacts, and a spring acting on said member to press said contactors toward said contacts.

9. In a circuit controlling device, a base, a plurality of contacts mounted on said base, a member mounted on said base for limited rotatory, axial and lateral movement with relation thereto and for tilting movement about a plurality of transverse axes, contactors carried by said member and movable thereby respectively into bridging relation to selected pairs of contacts, the contacts of each pair being arranged to enable the bridging contactor to engage the same with a wedging action to move about two intersecting axes with relation thereto, and yieldable means for pressing said member toward said base and imparting thereto such lateral and tilting movements as may be required to provide substantially equal contact pressure of said contactors on each contact of the selected pairs of contacts.

10. In an electric switch of the conventional multiple pole double throw type, two elements arranged in operative relation one to the other, a plurality of contacts rigidly secured to each element, the contacts on at least one of said elements having inclined contact surfaces, said elements being biased one toward the other and being relatively movable to effect selective engagement between the contacts carried by the respective elements, one of said elements being tiltable about a plurality of transverse axes to enable said engagement to be effected with substantially equal pressure at each point of contact engagement.

11. In an electric switch of the conventional multiple pole double throw type, a normally stationary element, a plurality of pairs of contacts rigidly secured to said element, a second element, and a plurality of contactors secured to said second element, said second element being rotatable to engage said contactors with selected pairs of contacts on said stationary element, the contacts of each pair being arranged to permit the engaging contactor to enter the space between the same and said second element being biased toward said stationary element, one of said elements being tiltable about a plurality of transverse axes to cause said contactors to engage each contact of the selected pairs of contacts with substantially equal pressure.

12. In a voltage changer for an electric motor or the like, two pairs of contacts mounted on said base and having means for connecting the same respectively with different parts of the motor circuit, a third pair of contacts mounted on said base and connected one with the other, a member mounted on said base for rotatory movement with relation thereto, and contactors carried by said member and movable by the rotation of said member into a position to connect the two contacts of each of the first mentioned pairs one with the other, or into a position to connect one contact of each of said first mentioned pairs with the respective contacts of said third pair.

13. In a voltage changer for an electric motor or the like, two pairs of contacts mounted on said base and having means for connecting the same

respectively with different parts of the motor circuit, a third pair of contacts mounted on said base and connected one with the other, a member mounted on said base for rotatory movement with relation thereto, and contactors carried by said member and movable by the rotation of said member into a position to connect the two contacts of each of the first mentioned pairs one with the other, or into a position to connect one contact of each of said first mentioned pairs with the respective contacts of said third pair, said member and said base having parts cooperating to positively prevent the movement of said member beyond either of said positions.

14. In a voltage changer for an electric motor or the like, a base, a plurality of contacts mounted on said base substantially in a common plane, a part of said contacts having means for connecting the same in a motor circuit, and a part of said contacts being permanently connected one with the other, a member mounted on said base for rotatory movement about an axis transverse to said plane, and bridging contactors carried by said member and movable by the rotation thereof into bridging relation to selected pairs of contacts, said contactors being movable transversely to said plane with relation one to the other to enable each contractor to firmly engage said contacts.

15. In a voltage changer for an electric motor or the like, a base, a plurality of contacts mounted on said base substantially in a common plane, a part of said contacts having means for connecting the same with the motor circuit, and a part of said contacts being permanently connected one with the other, a member mounted on said base for rotatory movement about an axis transverse to said plane, contactors carried by said member and movable by the rotation thereof into bridging relation to selected pairs of contacts, said member being tiltable with relation to said base and the contacts of each pair being arranged to permit the bridging contactor to enter the space between the same, and a spring acting on said member to press the latter into engagement with the respective contacts.

16. In a reversing switch, a base, a plurality of contacts mounted on said base substantially in a common plane, part of said contacts having means for connecting the same in a circuit, and another part of said contacts each being permanently connected with another contact, a member mounted on said base for rotation about an axis transverse to said plane, contactors carried by said member and movable by the rotation thereof either into positions to connect the first mentioned contacts in pairs independently of the last mentioned contacts, or into positions to connect the last mentioned contacts respectively with contacts of the first mentioned part, and means for maintaining said contactors in firm engagement with selected contacts.

17. In a reversing switch, a base, a plurality of pairs of contacts mounted on said base substantially in a common plane, two pairs of said contacts having means for connecting the same in a circuit and a third pair of said contacts being permanently connected with contacts of the respective first mentioned pairs, a member mounted on said base for rotation about an axis transverse to said plane, contactors carried by said member and movable by the rotation thereof either into bridging relation to the contacts of the respective first mentioned pairs or into bridging relation with one contact of each of the first men-

tioned pairs and the respective contacts of said third pair, and means for maintaining said contactors in firm engagement with selected contacts.

18. In a reversing switch, a base, a plurality of 5 pairs of contacts mounted on said base substantially in a common plane, two pairs of said contacts having means for connecting the same in a circuit and a third pair of said contacts being permanently connected with contacts of the respective 10 first mentioned pairs, a member mounted on said base for rotation about an axis transverse to said plane, contactors carried by said member and movable by the rotation thereof either into bridging relation to the contacts of the respective 15 first mentioned pairs or into bridging relation with one contact of each of the first mentioned pairs and the respective contacts of said third pair, said member being tiltable with relation to said base and said contacts being arranged to permit the 20 bridging contactor to enter the spaces between the same, and means for yieldably pressing said member toward said contacts.

19. In a reversing switch, a base, three pairs of contacts mounted on said base, the first and second 25 pairs of contacts having means for connecting the same in a circuit and the contacts of the third pair being separately and permanently connected with the respective contacts of the first pair, a member mounted for rotatory movement with relation to said base, two contactors carried by said member and movable thereby into bridging relation to selected contacts, said contacts being so arranged that when said member is in one position one of said contactors will connect the contacts of the first pair one to the other and the other contactor will connect one contact of the third pair with one contact of the second pair, and when said member is in another position the last mentioned contactor will connect said 35 contact of the third pair with the other contact of the second pair and the first mentioned contactor will connect with the other contact of the third pair with that contact of the first pair with which it is not permanently connected, and means acting on said member to cause said contactors to engage each of said contacts with substantially equal pressure.

20. In a circuit controlling device, a base, a plurality of contacts mounted on said base and arranged in two series, a member mounted on said base for rotatory movement with relation thereto, contactors carried by said member and movable

thereby into bridging relation to selected contacts of one series, a second member mounted on said base and connected with the first mentioned member for rotatory movement therewith, and contactors carried by said second member for movement thereby into bridging relation to selected contacts of the other series, said members being biased toward base and being separately tiltable with relation to said base, and said contactors and said contacts being shaped and arranged to cause said contactors to engage the respective contacts with a lateral wedging action which will permit the contactor to move about two intersecting axes.

21. In a circuit controlling device, a base, a 15 plurality of contacts mounted on said base and arranged in two series, a member mounted on said base for rotatory movement with relation thereto, contactors carried by said member and movable thereby by bridging relation to selected 20 contacts of one series, a second member mounted on said base and connected with the first mentioned member for rotatory movement therewith, contactors carried by said second member for movement thereby into bridging relation to selected 25 contacts of the other series, said members being tiltable with relation one to the other and with relation to said base, and spring means for pressing said members toward the contacts of the respective series.

22. In a circuit controlling device, a base provided in one side thereof with a circular cavity, two series of contacts mounted on said base and extending into said cavity, a disk-like member mounted in said cavity for rotatory movement, axial movement and tilting movement with relation to said base, said member having a cavity in its inner side, contactors carried by said member and movable thereby into bridging engagement with selected contacts of one series, a second 35 member mounted in the cavity in the first mentioned member for axial and tilting movement with relation to said first mentioned member and to said base and connected with said first mentioned member for rotatory movement therewith, contactors carried by said second member and movable thereby into bridging engagement with selected contacts of the other series, and separate springs acting on the respective members to press the same toward said contacts.
